LEE R. SAGER AND RAYMOND H. MITCHELL, OF MINNEAPOLIS, MINNESOTA.

PIECE FEEDER FOR FLATWORK IRONERS.

Application filed December 13, 1926. Serial No. 154,399.

Our invention has for its object to provide a relatively simple device for feeding flat laundered pieces to a flat work ironer, and to this end it consists of the novel devices 5 and combinations of devices hereinafter described and defined in the claims.

It is very difficult for an operator to feed a flat piece, such as a sheet, to an ironer so that the end thereof entering the ironer 10 is parallel to the axis of the cylinders or rolls, and at the same time held transversely taut so that said piece will enter the ironer smooth.

By the use of our invention, one end of a 15 flat piece may be secured and held transversely taut and then carried toward the ironer, and automatically released to the ironer for movement therethrough. While one end of the piece is thus held and being 20 carried to the ironer, the body of said piece is being smoothed out and put under a stretching action, so that the piece will enter the ironer smooth and without wrinkles.

The invention further provides means for 25 continuing the smoothing and stretching action of the piece after the same has been released from the carrier and is being fed into the ironer under the action thereof.

By the use of the invention, all danger 30 of an operator being hurt by the ironer during the feeding of a piece thereto is eliminated.

In the accompanying drawings, which 35 illustrate the invention, like characters indicate like parts throughout the several views.

Referring to the drawings:

Fig. 1 is a right side elevation of the invention, and also showing a flat work ironer partly in longitudinal central section and 40 partly in diagram;

Fig. 2 is a fragmentary view corresponding to Fig. 1 with the exception that the feeder is shown partly in central longitudinal section and with some parts shown in 45 different positions, by means of broken lines;

Fig. 3 is a plan view of the invention, on an enlarged scale;

Fig. 4 is a fragmentary perspective view 50 of the carrier, as shown by full lines in Fig. 1;

Fig. 5 is a fragmentary detail view with some parts sectioned on the line 5—5 of Fig. 3; and

Fig. 6 is a fragmentary detail view taken 55 on the line 6—6 of Fig. 2 on an enlarged scale.

For the purpose of illustrating the relation of the invention to a flat work ironer, such an ironer is diagrammatically illustrated in the drawings, and of the parts thereof, it is important to note the frame 7, upper and lower steam cylinders 8 and 9 respectively, upper and lower aprons 10 and 11 respectively, feed ribbon 12 and deck 13 therefor, guide rolls 14 co-operating with 60 the upper cylinder 8, and delivery board 15. The parts thus far referred to are of standard and well known construction.

Referring now in detail to the invention, the numeral 16 indicates a frame having an 70 inclined top extension 17 which overlies the feed ribbon 12 and extends substantially parallel to the top or operating surface thereof. Mounted in the frame 16 are inner and outer baskets 18 and 19 respectively. 75 Extending transversely of the frame 16 between the baskets 18 and 19, is a brush comprising bristles 20 which extend above said baskets and are secured to a back bar 21 in the basket 19.

A U-shaped rack or carrier 22 has the outer ends of its arms pivoted at 23 to the top side members of the frame 16 substantially at the junction of the top extension 17 therewith. The mounting of the carrier 22 on the frame 16 is such as to permit vertical swinging movement of said carrier over the frame 16 from its dotted line position to its full line position shown in Fig. 2. Said carrier 22, when in its dotted line position, 80 overlies the frame 16 with its transverse member just outside of the basket 18, and when in said full line position, said carrier extends substantially parallel over the frame extension 17, with its transverse member 85 substantially overlying the delivery end of the feed ribbon 12.

When the carrier 22 is in said dotted line position, it loosely rests on buffers 24 on the frame 16, and when in said full line position rests on buffers 25 on the frame top extension 17.

The transverse member of the carrier 22 affords a relatively fixed clamping member 27, and co-operating with the end portions thereof are two endwise spaced clamping bars 28, each of which is independently attached to the outer edge portion of said member 27 by a spring hinge 29 under strain to open the respective clamping member, as shown by dotted lines in Fig. 5. Each clamping bar 28 is provided with a handle 105 110

30 by which it may be closed against the tension of its spring hinge 29. Said clamping bars 28 are also provided with latch plates 31 which project from the outer end thereof. Latches 32 are intermediately pivoted to the arms of the carrier 22 for engagement with the latch plates 31, to hold the clamping bars 28 pressed onto the clamping bar 27. Coiled springs 33, anchored to 10 the arms of the carrier 22 are attached to the outer end portions of the latches 32 and yieldingly hold said latches engaged with the latch plates 31.

Toggle levers 34 have one of their members pivoted to the arms of the carrier 22, and their other members pivoted to the latches 32 and positively hold said latches engaged with the latch plates 31.

Abutments 35 on the side members of the frame top extension 17 are arranged to be engaged by the toggle levers 34 during the movement of the carrier to its full line position in Fig. 2, and thereby buckle said toggle levers and operate the latches 32 20 against the action of the springs 33 to release the clamping bars 28, and permit the same to be opened by their spring hinges 29, as shown by dotted lines in Fig. 5. A long roll 36 is journaled to the arms of the carrier 22 just inside of the clamping bar 27 and extends parallel thereof. A brush, similar to the brush 21, has its back bar 37 secured to the arms of the carrier 22, and its bristles 38 project upward when said carrier 30 is in its full line position shown in Fig. 2. A long rod 39 is flexibly connected at 40 to the opposite side of the clamping bar 27 from the clamping bars 28 for swinging the carrier 22 to and from its full line position, 40 as shown in Fig. 2. Buffers 41 on the clamping bar 27 limit the opening movements of the clamping bars 28.

The operation of the invention may be briefly described as follows:

45 Laundered flat pieces to be ironed are placed in the basket 19 and picked out, one at a time, shaken out and placed in the basket 18 in position to be fed to the ironer. It is, of course, understood that the ironer is, 50 at this time, heated and running, and that the carrier 22 is positioned as indicated by broken lines in Fig. 2. In this position of the carrier 22, the clamping bars 28 are at the top of the clamping bar 27 and are 55 yieldingly held open by their spring hinges 29.

In the basket 18 is a sheet α to be ironed. One end of this sheet is laid over the clamping bar 27 and one of the clamping bars 60 28 is pressed onto the same by taking hold of its handle 30 and swinging said bar against the action of its spring 29 onto the respective corner portion of the sheet α . While this clamping bar 28 is thus held, the 65 adjacent latch 32 is operated to engage its

latch plate 31 by straightening the toggle 34 attached to said lever, as best shown in Fig. 4. With one corner of the sheet α thus held, the respective end of the sheet is transversely stretched, and its opposite corner secured by the other clamping bar 28. After the sheet α is attached to the carrier 22, said carrier is swung by the hand rod 39 from its dotted line position to its full line position in Fig. 2. During this swinging movement of the carrier 22 the sheet α is carried over and onto the brush bristles 20 which operate to spread the sheet α out and also produce sufficient drag thereon to stretch said sheet out flat. While this movement of the carrier 22 is taking place, the operator may assist in shaking out and straightening the sheet so that it will lie flat on the brush bristles 20. Just before the carrier 22 comes to rest on the buffers 25, the toggle levers 34 engage the abutments 35 and are buckled thereby to operate the latches 32 and release the clamping bars 28.

Upon the releasing of the clamping bars 28, their spring hinges 29 swing the same into open positions, as shown by broken lines in Fig. 5, and thereby release the held end of the sheet α and permit the same to drop onto the feed ribbon 12. The travelling action of this feed ribbon 12 will carry the adjacent end of the sheet α under the first roll 14 and onto the steam cylinder 8 which continues the feeding action of the sheet α into the ironer. During the swinging movement of the carrier 22 just described, the clamping bars 28 have been reversed and are on the under side of the clamping bar 27, so that the sheet is free to drop onto the feed ribbon 12. This reverse action of the carrier 22 also brings the brush bristles 38 into operative positions so that the sheet α rests thereon and the smoothing and spreading action started by the bristles 20 is continued by the bristles 38 during the feeding of the sheet into the iron under the action thereof.

The purpose of the roll 36 is to facilitate the movement of the sheet α onto the clamping bar 27 when securing the same by the clamping bars 28.

After the sheet α is passed over the brush bristles 38, the operator returns the carrier 22 to its original position by means of the hand rod 39.

By the use of the above described invention, flat pieces may be very quickly and accurately fed to the ironer so that they are ironed perfectly smooth without wrinkles or creases.

As previously stated, by the use of the 125 feeder, all danger of an operator being hurt by the ironer is eliminated.

In actual practice, the piece-engaging surface of the clamping bar 27 will be covered with a cushion strip, such as cotton, felt 130

or the like. Such a cover will assist in causing the piece held by the clamps to more freely let go of the carrier 22 so that the same will drop smoothly onto the feed ribbon 12.

What we claim is:

1. In a feeder of the kind described, the combination with a frame, of a carrier having a piece-holding clamp and mounted on the frame for movement to and from a piece-releasing position, means for releasing the clamp, and a piece-holding basket on the frame from which a piece is drawn by the carrier during its movement to the piece-releasing position.

2. The structure defined in claim 1 in further combination with a brush over which the piece held by said clamp is drawn by the carrier during its movement to said piece-releasing position.

3. In a feeder of the kind described, the combination with a frame, of a carrier having a piece-holding clamp and mounted for swinging movement to and from a piece-releasing position, automatic means for releasing the clamp during the swinging movement of the carrier to its piece-releasing position, and a hand rod on the carrier by which said carrier may be swung to and from its piece-releasing position.

4. In a feeder of the kind described, the combination with a frame, of a carrier having a piece-holding clamp and mounted for swinging movement to and from a piece-releasing position, automatic means for releasing the clamp during the swinging movement of the carrier to its piece-releasing position, and a piece-holding basket on the frame from which a piece is drawn by the carrier during its movement to and from the piece-releasing position.

5. In a feeder of the kind described, the combination with a frame, of a carrier having a piece-holding clamp and mounted for swinging movement to and from a piece-releasing position, automatic means for releasing the clamp during the swinging movement of the carrier to its piece-releasing position, a piece holding basket on the frame from which a piece is drawn by the carrier during its movement to the piece releasing position, and a brush over which the piece in the basket is drawn by the carrier during its swinging movement to said piece-releasing position.

6. In a feeder of the kind described, the combination with the frame, of a carrier mounted on the frame for movement to and

from a piece-releasing position, a spring-released piece-holding clamp on the carrier, a latch for holding the clamp operative, a toggle lever holding the latch operative, and an abutment for buckling the toggle lever during the movement of the carrier to said piece-releasing position to operate the latch and release the clamp.

7. In a feeder of the kind described, the combination with a frame having an inclined extension adapted to overlie the feed ribbon of a flat work ironer, of a carrier having a piece-holding clamp and mounted on the frame for swinging movement to and from a piece-releasing position in which it overlies said frame extension, and automatic means for causing the clamp to release the held piece.

8. In a feeder of the kind described, the combination with a frame, of a carrier having a pair of spring-released piece holding clamping members, latches for holding the clamping members operative, said carrier being mounted for movement to and from a piece-releasing position, and automatic means for simultaneously operating said latches to release the clamping members.

9. In a feeder of the kind described, the combination with a frame, of a carrier having means for holding one edge of a piece thereon, and means for operating the carrier to cause the same to spread out the piece and then release the same.

10. In a feeder of the kind described, the combination with a frame, of a carrier, clamping means for holding one edge of a piece transversely stretched on the carrier, means for operating the carrier to spread out the piece, and means for releasing the piece at the limit of the movement of the carrier to spread out said piece.

11. In a feeder of the kind described, the combination with a frame, of a carrier, clamping means for holding one edge of a piece transversely stretched on the upper face of the carrier, means for operating the carrier to spread out the piece and for reversing the carrier to bring the held edge of the piece and the clamping means on the under side thereof, and means for releasing the clamping means and moving the same from under the held edge of the piece at the limit of the movement of the carrier to spread out said piece.

In testimony whereof we affix our signatures.

LEE R. SAGER.

RAYMOND H. MITCHELL.
